UNITED STATES PATENT OFFICE.

ANTON BECKER, OF CHICAGO, ILLINOIS, ASSIGNOR, BY MESNE ASSIGNMENTS, TO RALSTON CAR COMPANY, OF CHICAGO, ILLINOIS, A CORPORATION OF ILLINOIS.

METALLIC FLUSH-FLOOR DUMP-CAR.

SPECIFICATION forming part of Letters Patent No. 763,947, dated June 28, 1904.

Application filed January 23, 1904. Serial No. 190,415. (No model.)

To all whom it may concern:

Be it known that I, ANTON BECKER, a citizen of the United States, residing at Chicago, in the county of Cook and State of Illinois, have invented a new and useful Metallic Flush-Floor Dump-Car, of which the following is a specification in its best form now known to me, reference being had to the accompanying drawings, in which similar numerals indicate the same parts throughout the several views.

My invention relates to metallic cars capable of being unloaded by the mere opening of a series of doors.

The object of my invention is to provide such a car in which the floor is flush and smooth when the doors are closed and to provide means by which the car is self-cleaning, so that when unloading is attempted all of the load is automatically removed.

My invention consists in a car capable of accomplishing the above objects which can be easily and economically constructed, which will not readily get out of order, and which can be easily and cheaply repaired.

It also consists in a novel form of end sill and bolster and means for attaching the draft-rigging, adapted to assist in the accomplishment of the general objects of the invention.

It also consists in novel arrangements of parts and other features, which will hereinafter be more fully described and claimed.

In the drawings, Figure 1 is a side elevation, and Fig. 2 is a plan view, of approximately one-half of a car, showing my invention in its preferred form. Fig. 3 is a partial end view of the car, showing the end sill and draw-bar attachment. Fig. 4 is a detail sectional plan view taken on line 4 of Fig. 3. Fig. 5 is a detail sectional side view of the end sill, taken on line 5 of Fig. 3. Fig. 6 is a sectional view taken on line 6 of Fig. 1, showing one of the several cross-bearers of the car. Fig. 7 is a detail view of a portion of a cross-bearer, showing the method of attachment of wings which protect the edges of the doors of the car in a manner to be hereinafter described. Fig. 8 is a detail end

view taken on line 8 of Fig. 6, showing the double stake for the box, which, as shown in Fig. 1, is used at the center of the car and at the bolster. Fig. 9 is a sectional end view on line 9 of Fig. 1, showing the bolster and the construction for attaching the draft-rigging. Fig. 10 is a sectional view through the cross-bearer, taken on line 10 of Fig. 9, showing particularly the wings heretofore mentioned. Fig. 11 is a detail view of the rack applied to the cross-bearers. Fig. 12 is a view from the bolster to the end of the car, taken partly in section on line 12 of Fig. 3 and partly as a side view on line 12^a of Fig. 9. Fig. 13 is a partial detail plan view taken on line 13 of Fig. 12.

In the preferred form of my invention I provide an underframe having extending from end to end of the car, through its center, a central plate 25, the plate being cut away, as shown in Fig. 12, to provide for the king-pin and draw-bar yoke, this cut-away being indicated by the lines 26, 27, 28, and 29. The full depth of this plate between the bolsters is, as shown, the full depth of the underframe. The central plate 25 has on its lower edge a flanged plate 32, running, as shown in Figs. 1 and 12, from a point beyond one bolster to a corresponding point at the other end of the car beyond the other bolster. This web-plate 25 and flanged plate 32 are connected together by angles 33 and 34, running from bolster to bolster, as shown. Connected to this central plate-girder, just described, are a series of cross-bearers, as shown in Fig. 1. These cross-bearers at the bolsters are double, with flanges extending in both directions, and at other points the cross-bearers are single, with flanges extending in only one direction. The opposite halves of these cross-bearers may be made of pressed steel shapes of the size and form desired, or they may be made of webbed plates and flanged angles, as desired. For convenience of illustration I have shown half of the cross-bearers as composed of plate 40, forming the web of one-half of the cross-bearer, the same having pressed flanges 41, 42, and 43. On the oppo-

site side of the central plate 25, heretofore referred to, is a corresponding plate 46, having corresponding pressed flanges 47 and 48, &c. The two flanges 44 and 47 of these corresponding plates 46 and 40 are shaped as shown in Fig. 6, so that they fit snugly over the central plate 25, the angles 33 and 34, and the flanged plate 32, and are secured to these various parts by rivets 50 51 52 53 54, &c., as shown in Fig. 6. The lower flanges 41 and 48 of the cross-bearer are for purpose of clearance and convenience in angular form, as shown in Fig. 6. The cross-bearer is strengthened by a plate 60, extending from side to side of the car, running crosswise of the underframe of the car, secured to the flanges 41 and 46, heretofore described, by rivets 61 and to the flanged plate 32 and angles 36 and 34 by rivets 50 and 51, heretofore described. Similarly the underframe of the car is strengthened and formed by another reinforcing-plate 65, extending across the top of the underframe and the top of the cross-bearer flanges and secured to said flanges by rivets 66. (See Fig. 6.)

Secured to the ends of the bolsters and cross-bearers by rivets 68 and also independently secured to the ends of the car are stakes 69, made, as shown, of double angle-irons at the center and bolster and of single irons elsewhere.

Secured to the upper reinforcing-plates, heretofore referred to, are a series of castings 71, 72, and 73. Through these castings, just described, is a rod or shaft 75, on which are journaled or hinged oppositely-disposed wings 76 and 77, which in the manner to be hereinafter described operate to make that portion of the car over the cross-bearers self-cleaning. In commercial practice each of these wings is approximately four inches from the center of the rod 75 to the outer edge of the wing. These hinged wings are so made that they extend clear across the top of the cross-bearers of the car, as shown in Fig. 2, but are preferably cut away at the center in angular lines 80 and 81, so that they may operate properly in connection with the dumping-doors, as will be hereinafter described.

At intervals along the top of the center-plate 25, heretofore referred to, are a series of hinge-supports 85. These hinge-supports 85 are connected by a rod, or preferably by a series of short rods 86, on which are journaled or hinged floor-sections or doors 88, made up, preferably, of large plate, which just fit in between the central plate-girder of the underframe of the car, the cross-bearers, heretofore described, and the side of the car. (See Fig. 2.) These doors are, as shown in Fig. 2, substantially the same size between the bolsters, while the doors 89 at the end of the car outside the bolsters are for convenience made slightly larger; but manifestly the car may be so designed that they are of approximately

the same size as the other doors. These doors, as shown in Fig. 6, are adapted to be moved to a horizontal position, in which position they form sections of the floor of the car, and are also adapted, as shown in the full lines on the right of said figure and the dotted lines of the same figure, to be tilted downward, so that material upon them will slide off. These motions of the doors of the car may be made by hand or by any of several forms of mechanical devices, one of which will be hereinafter fully described. On the edges of the doors 88 adjacent to the cross-bearers are secured plates 90, adapted to fit under the edges of the wings 76 and 77, mounted on the tops of the cross-bearers, as heretofore described, in order, as shown in Fig. 10, to make the floor approximately level. Below these plates 90 are secured reinforcing angle-irons 91, and in order to use the operating mechanism, to be hereinafter described, I extend one of these angle-irons 91 beyond the inner end of the reinforcing-plate 90 to form the slot 92, Figs. 9 and 10, for guides 93 to travel in.

Cut in the plates 40 on one side of all of the cross-bearers are angular parallel slots 95, and on the opposite plates 46 are cut other corresponding parallel slots 96. Running the entire length of the car through these slots and on the opposite sides of the car are two shafts 98 and 99. Mounted upon said shafts are pinions 100, meshing in racks 101, rigidly secured to the under side of the slots 95 and 96, heretofore referred to, from which it will be seen that if the pinions 100 travel up and down the racks 101 the shafts 98 and 99 will be moved from the outer ends of the slots 95 and 96 to the inner ends thereof, and vice versa. Also mounted upon shafts 98 and 99 are guides 93, heretofore referred to, adapted to slide backward and forward in the slots 92, and anti-friction-rollers 103, adapted to bear against the under side of the door (see Fig. 10) and move along from the side of the car to the center, and vice versa, from which it will be seen that by moving the shafts 98 and 99 from the side of the car to the center the door 88 will through the agency of guide 93 and wheels 103 move the door downward to the dotted-line position against the resistance of foreign obstructions and that moving the shaft in the opposite direction will move the door from the dotted-line position shown at the left of Fig. 6 to the full-line position, where the door is again in line with the floor. On the outer end of these shafts 98 and 99 and outside the end sill, as shown in Figs. 2 and 3, are ratchet-wheels 105, adapted to be engaged by pawls 106 of the universal levers 107 of the ordinary construction, the operating of these levers being adapted to move the shafts 98 and 99, with the parts heretofore described attached to them, along the racks 101 from the outer end of the slots 96 and 97 to the inner ends.

As heretofore described, when the floor-

doors 88 are level the wings 76 and 77, mounted on the tops of the cross-bearers, are level with the edges of the doors. As the doors are lowered in the manner described in the last paragraph these wings 76 and 77 descend from the full-line horizontal position of Fig. 10 to the dotted angular line position, as shown in Fig. 10, the angular edges 80 and 81 of said wings sliding along the central portions of the doors. The change to the tilted position causes all dirt and other material which in the loaded car rested upon the tops of the wings 76 and 77 over the cross-bearers to slide off from them, thereby cleaning that portion of the car which is over the cross-bearers. This is an important feature of my invention, as experience shows that without this device or its equivalent a very substantial percentage of the load of the car remains upon the cross-bearers and is not emptied out when the car is unloaded. When now the doors are elevated in the manner heretofore described, the doors themselves lift these wings 76 and 77 from the inclined position shown in Fig. 10 to the full-line position, where the floor of the car is again level.

The box of the car is formed by riveting to the inside of the stakes 69, heretofore referred to, plates 110 and reinforcing the tops with an angle-iron 111, having one flange projecting over the top of the stakes, as shown in Fig. 9, thereby making a smooth neat edge to the top of the box of the car. The angle-irons at the side and ends of the car are joined by neat plates 112, as shown in Fig. 2. The stakes are reinforced and secured to the under frame of the car by an angle-iron 114, secured by rivets to the stakes and to the bottom of the car, as shown in Fig. 9, the angle-iron 114 and the flange 43 of the cross-bearer web 40 being supported by castings 115, which serve to give greater strength and rigidity to the connection between the stake and the top of the cross-bearer. The lower flange of this angle 114 extends, as shown in Figs. 9 and 10, over the edge of block 115, so as to make a jam or stop for the doors of the car to bear against when the door is up. Stops 145 are placed on the cross-bearers to limit the downward motion of the door. In order to reinforce the side of the box of the car outside of the bolsters, I rivet to the side plates 110 two U-shaped angle-irons 117 and 118, the bottoms of the U-shaped angle-irons being placed back to back and riveted together, as shown in Fig. 1. In order to carry off water from the tops of the angles, a slight clearance should be left between the bottoms of the U's where riveted together. I find that this construction greatly increases the strength and rigidity of the end of the car. In order to provide means for attaching one of the several forms of draft-rigging, I provide between the bolster and end sill a housing (illustrated in Fig. 9) consisting, preferably, of two channel-irons 120, se-

cured to the bottom flanges of the bolster by suitable rivets and reinforcing-plates and having an inverted-V shape composed of pressed plates 121, secured by rivets 122 to the central web-plate 25 and by rivets 123 to the tops of the channel-irons 120. By making the top of this housing of this inverted-V shape I allow the floor-doors 88 to swing down, as heretofore described, and also allow ample room for the various parts of the draft-rigging.

In order to provide for removing the draw-bar while providing strength for the car and in order to have the draw-bar at the proper height while keeping the car low upon the tracks, I have the outer end of the channels 120 rolled upward, as shown in Fig. 12, and secure across their under sides by bolts 140 an angle-iron 126 and secure to the angle-iron and to the ends of the channels or corresponding members 120 an end plate 127, the same having an inverted-U-shaped notch cut in it, forming a hole 128 above the angle-iron 126, through which the draw-bar is adapted to pass. In order to further strengthen the end sill, I secure to this plate 127 and to the webs of the end sill a casting 130, (shown in detail in Fig. 3,) having in its center a reinforcing-rib 131. This construction gives the end of the car great rigidity, so that there is no danger of the draw-bar or draft-rigging being torn from the car with any ordinary strain.

The inverted-U-shaped cut is, as shown in Fig. 12, carried into the L-shaped plate 134 in the end sill, to be more fully described hereinafter.

In order to provide an end sill outside of the underframe of the car corresponding to the dead-wood of an ordinary car, I secure to the under side of the end of the car channel-irons 133, having their ends inclosed in L-shaped sections 134, and secure the whole together by a Z-bar 135, secured to the end of the car and to the channel and to the L-shaped sections by suitable rivets, as shown in Figs. 4 and 5. The corner of the end sill is capped by a push-pole pocket 136. This pocket connection further strengthens the connection between the L-shaped pieces and the channel. The connection between the end sill and the car-body is further strengthened by the insertion of an angle 138, Fig. 12, secured by rivets to the top of the Z-bar on the end sill and to the end of the stakes. The center plate 25 is rigidly secured to the end sill by angle-irons 139, secured to the center plate and to the top of the end sill, particularly to the Z-bar, and they are also connected to the angles 138, just described. (See Fig. 12.)

I do not wish to be understood by referring to channels or angle-irons or any similar shape to mean that there is any distinction for the purposes herein used between the commercial forms, pressed forms, or built-up forms. Neither do I wish to be limited to the exact

details of construction, which may be varied within reasonable limits without departing from the principles of my invention.

Having thus described my invention, what I claim as new, and desire to secure by Letters Patent, is—

1. In a car, the combination of an under-frame composed of a central girder running lengthwise of the car, with cross-bearers at right angles to said central girder; and a door between two cross-bearers pivotally mounted substantially at the top of the center of said central girder adapted to swing up and form a part of the floor of the car and adapted to swing down about said pivotal point and permit a load upon the door to slide outward from the center of the car.

2. In a car, in combination with an under-frame of the car consisting of a central girder running lengthwise of the car and cross-bearers across the car at right angles to said girder; doors pivoted back to back on the top of said girder between a pair of cross-bearers adapted to form a part of the floor of the car and adapted to swing down between said bearers and permit a load upon the door to slide outward from the center of the car.

3. In a metallic car, the combination of a series of cross-bearers, one central plate-girder extending longitudinally of the car and intersecting said bearers in their centers, doors pivotally mounted at the top of said girder and at the center thereof between said bearers adapted to swing up and form a part of the floor of the car and adapted to swing down about said pivotal point and permit a load upon the door to slide outward from the center of the car.

4. In a metallic car, the combination of cross-bearers, one central plate-girder extending longitudinally of the car and intersecting said bearers in their centers, doors pivotally mounted at the top of said girder and at the center thereof between said bearers adapted to swing up and form a part of the floor of the car and adapted to swing down about said pivotal point and permit a load upon the door to slide outward from the center of the car and mechanism for so moving the doors.

5. In a car, the combination of a series of cross-bearers running across the car, doors adapted, when closed, to close the space between the tops of said bearers and form the floor of the car, and adapted, when open, to permit a load to slide off from them at the side of the car, a plate or wing pivoted upon or adjacent to said bearer, parallel to its length, adapted, when the door is closed, to lie in a position substantially level with the floor and adapted, when the door is released or open, to tilt so that portions of the load upon said plate will slide off from the same, thereby cleaning the portion of the floor over said bearer, substantially as described.

6. In a car in combination with the cross-

bearers of the car, two doors or plates running lengthwise of the cross-bearer across the car, pivoted back to back on the top of said bearer, adapted, when swung up level, to form a part of the floor of the car, and adapted, when released, to fall to an angular position, whereby portions of the load upon said plates slide off from them.

7. In a car, a rod or shaft running along a cross-bearer of the car, two plates pivotally mounted on said rod adjacent to said cross-bearer so that when raised they form a portion of a horizontal floor and when released they fall into an angular position, whereby portions of the load upon said angular plates slide off from them.

8. In a metallic car the combination of a center vertical plate - girder extending the length of the underframe of the car, a series of cross-bearers and bolsters along said plate-girder, and a support or housing for the draft-rigging at the end of the car consisting of two vertical channel-irons secured to said cross-bearers on opposite sides of said plate and at a distance therefrom, and an inverted-V-shaped top of metal secured to said channel-irons and to said plate, substantially as described.

9. In a metallic car the combination of a central vertical plate - girder extending the length of the underframe of the car, a stake 95 69, extending upward from a point near the end thereof, a bracket 138, secured to said stake, a Z-bar 135 secured to said bracket 138 and to said stake, an L-piece 134 secured to said L-bar forming the end of the end sill, 100 and angle-irons 139 inside the end sill adapted to secure said end sill to said center plate, substantially as described.

10. In a metallic car, the combination of a car and an end sill composed of channel-irons 105 133 secured to the bottom of the opposite sides of the car extending from the end of the car, an L-shaped piece fitting over the ends of said channel-irons and a Z-bar 135 fitting over the end of said L-bar, secured to said L-bar, the 110 tops of said channels, and to the stakes of the box of the car, substantially as described.

11. In a metallic car, the combination of a central plate running the length of the under-frame of the car, two half-portion cross-bearers secured on opposite sides of said plate and to each other, angle-irons at the bottom of said plate also secured to said cross-bearers and reinforcing-plates secured across the top and bottom of the cross - bearer halves, substantially as described.

12. In a metallic car, the combination of a cross-bearer plate, a stake secured to the end thereof, a block secured to the top of said plate and an angle-iron extending around the 125 inside of the edge of said car secured to said block, the edge of said angle extending over the edge of said block so as form a door-stop, substantially as described.

13. In a metallic car, the combination of a 130

central plate-girder extending through the car, a series of hinge-supports secured to the top of said plate extending upward in the central plane of the plate and doors pivotally mounted on said supports on opposite sides of said girder, substantially as described.

14. A freight-car having its load-carrying floor composed of a set of drop-doors and narrow floor-plates normally in substantially the same horizontal level plane, said floor-plates being so pivotally mounted between the doors that when the doors are opened they tilt downward toward the doors, whereby portions of the load upon the floor-plates slide off onto the doors, substantially as described.

15. A car having a center sill and cross-sills and a floor mounted upon the same composed of a set of drop-doors arranged in two series, one series on each side of the center sill and a plurality of narrow floor-plates mounted upon the cross-sills between the doors and in the plane thereof, said narrow floor-plates being pivotally mounted so that when the doors are

open the plates tilt toward the doors, whereby portions of the load upon the plate slide off onto the doors and the entire floor of the car is emptied.

16. In a car in combination with the sides and ends of the dump-car body; widely-spaced cross bearers or beams extending from side to side of the car supporting said car-body, a series of drop-doors constituting the floor of the car-body mounted so as to drop between said cross bearers or beams, and narrow floor-plates pivotally mounted between successive doors in such a way that they are normally level with the doors, and that when the doors are opened said floor-plates tilt toward the doors, whereby portions of the load upon said plates are ejected upon the doors and the entire floor of the car is cleaned.

ANTON BECKER.
